UNITED STATES PATENT OFFICE.

WILLIAM B. CLAYTON, OF WAYLAND, NEW YORK.

VENTILATOR.

1,285,045.

Specification of Letters Patent. Patented Nov. 19, 1918.

Application filed July 20, 1918. Serial No. 245,389.

To all whom it may concern:

Be it known that I, WILLIAM B. CLAYTON, a citizen of the United States, residing at Wayland, in the county of Steuben and

5 State of New York, have invented certain new and useful Improvements in Ventilators, of which the following is a specification, reference being had to the accompanying drawings.

10 This invention relates to certain improvements in ventilators and has relation more particularly to a device of this general character especially designed and adapted for use in connection with a window and it is an object of the invention to provide a novel and improved ventilator which, in addition to permitting the escape of vitiated air prevents the ingress of insects.

15 It is also an object of the invention to provide a novel and improved ventilator including a hood which offers no hindrance to the required ventilation but serves effectually as a storm shield.

20 The invention consists in the details of construction and in the combination and arrangement of the several parts of my improved ventilator whereby certain important advantages are attained and the device rendered simpler, less expensive and otherwise more convenient and advantageous for use, as will be hereinafter more fully set forth.

25 The novel features of my invention will hereinafter be definitely claimed.

30 In order that my invention may be the better understood, I will now proceed to describe the same with reference to the accompanying drawings, wherein:

35 Figure 1 is a vertical sectional view taken through a ventilator constructed in accordance with an embodiment of my invention, the coacting window frame being shown in fragment.

40 Fig. 2 is a fragmentary view in rear elevation of my improved ventilator as herein set forth.

45 Fig. 3 is a fragmentary view in perspective of my improved ventilator as herein disclosed, and

50 Fig. 4 is a fragmentary sectional view illustrating a connection between the ventilator and the coacting window frame.

55 As herein disclosed my improved storm shield comprises two substantially duplicate sections in telescopic engagement so that the device may be adjusted in accordance with

the requirements of practice to permit its use in connection with window frames or the like of differing widths.

As is disclosed in the accompanying drawings each of the sections A and A' of my improved ventilator comprises a top plate 1 disposed on a predetermined downward and outward incline having one end portion provided with an integrally connected end 60 wall 2 substantially in the form of a right-triangle. The upper marginal portion of the plate 1 is provided with the inwardly directed flange 3 substantially horizontally disposed when the ventilator is in applied 65 position and the apex portion 4 of the end wall 2 is bent to overlap the adjacent end portion of the flange 3. The lower marginal portion of the plate 1 of the section A is returned upon itself to afford a guideway 70 in which is slidably engaged the lower marginal portion of the plate 1 of the section A'. The flange 3 of the plate 1 of the section A' also overlies and contacts with the flange 3 of the section A so that the sections 75 A and A' are effectively maintained in assembled relation.

In practice my improved ventilator is interposed between the vertical stiles of a window casing at the top thereof and outwardly 80 of the upper sash and the vertical marginal portions of the end plate 2 of the sections A' are anchored to the vertical stiles of the casing by the screws 6 or the like disposed through the lower portion of the end walls 2 85 and engaging the stiles of the casing. If desired, screws 7 or the like may be disposed through the flanges 3 and engage with the top or crown piece of the window casing. Coacting with each of the sections A and A' 90 is a screening element S of a length substantially co-extensive in length with the length of the section and of a width substantially equal to the major height of the section or that portion of the section at the inner face 95 thereof. The outer end of the screening element S is provided with the inwardly directed flange 8 overlying the vertical marginal portion of the end plate 2 and pivotally secured thereto adjacent its top by the 100 rivet 9 or the like. The lower portion of the flange 8 is adapted to have disposed there-through an anchoring screw 6 hereinbefore referred to.

110 In practice the upper sash of the window is adapted to be lowered with its upper rail immediately adjacent the lower portion of

the ventilator so that vitiated air within the room may readily pass therefrom. It will also be self-evident that the screening elements S serve effectively to prevent ingress of insects while the hood structure as afforded by the plates 1 and 3 serves as a storm shield.

It has also been found of advantage to employ in connection with the lower marginal portions of the overlapping portions of the screening elements S the spring clip C whereby the elements S are effectively maintained in assembled relation.

I claim:

- 15 1. A ventilator comprising two substantially duplicate sections, one section having telescopic engagement with the other, each of said sections having a downwardly and outwardly inclined top plate, and an end plate substantially triangular in form, the upper marginal portions of the top plate being provided with substantially horizontally disposed flanges, the lower marginal portion of one of the top plates being provided with a guideway to receive the lower marginal portion of the top plate of the second section.
- 20 25 2. A ventilator comprising two substantially duplicate sections, one section having telescopic engagement with the other, each of said sections having a downwardly and outwardly inclined top plate, and an end plate substantially triangular in form, the upper marginal portions of the top plate being provided with substantially horizontally

disposed flanges, the lower marginal portion 35 of one of the top plates being provided with a guideway to receive the lower marginal portion of the top plate of the second section, the flange of the second section underlying the flange of the first section. 40

3. A ventilator comprising two substantially duplicate sections, one section having telescopic engagement with the other, each of said sections having a downwardly and outwardly inclined top plate, an end plate 45 substantially triangular in form, the upper marginal portions of the top plate being provided with substantially horizontally disposed flanges, the lower marginal portion of one of the top plates being provided with a 50 guideway to receive the lower marginal portion of the top plate of the second section, the flange of the second section underlying the flange of the first section, and a screening element secured to the vertical marginal 55 portion of the end plate of each of the sections, said screening element being of substantially a length co-extensive with the length of the section and of a width substantially equal to the height of the vertical margin of the end plate. 60

In testimony whereof I hereunto affix my signature in the presence of two witnesses.

WILLIAM B. CLAYTON.

Witnesses:

CHARLES C. FALTS,
Wm. N. SAMBIER.
